their Attorney.

UNITED STATES PATENT OFFICE.

JACOB A. HYLE AND JACOB W. HERMAN, OF HARRISBURG, PENNSYLVANIA, ASSIGNEES TO THE RAILWAY TIE CORPORATION, OF CHICAGO, ILLINOIS, A CORPORATION OF DELAWARE.

METALLIC RAILWAY-TIE AND RAIL-FASTENING.

1,205,897.

Specification of Letters Patent.

Patented Nov. 21, 1916.

Application filed July 20, 1916. Serial No. 110,288.

To all whom it may concern:

Be it known that we, JACOB A. HYLE and JACOB W. HERMAN, citizens of the United States, residing at Harrisburg, in the county of Dauphin and State of Pennsylvania, have invented certain new and useful Improvements in Metallic Railway-Ties and Rail-Fastenings, of which the following is a specification.

10 Our invention relates to the construction of railway ties and means for firmly and securely fastening the track rails in proper position on the ties of steam and electric railways.

15 The main object of this invention is to provide a simple, durable, economical and efficient metal railway tie and rail fastening means possessing sufficient strength to successfully withstand all the strains to which 20 the tie and rail fastening means are ordinarily subjected when in service and which are so constructed that the longevity of the same is materially increased.

25 Another object of the invention is to provide a metallic railway tie, in connection with wooden blocks constituting a resilient support for the track rails and a thorough and reliable insulation of the rails so as to render them efficient as conductors in the 30 usual automatic electrical signaling systems.

35 A further object of the invention is to so construct our improved railway tie that the number of ties required per mile of road bed is materially reduced. And still further objects of the invention are to so construct the tie that the wooden blocks utilized in connection therewith may be readily removed 40 therefrom and a new block replaced by one employee and without removing the tie, or in any manner disturbing the position of the track rail or ballast beneath the tie; to provide improved means for safely and firmly securing the wooden blocks to the tie thereby maintaining absolute safety in the 45 gage of the track rails, and to secure the track rails in their proper position upon the wooden blocks by means of the ordinary plain spike or screw spike now in general use and employed in most all railways for

50 the purpose of securing the track rails to a wooden tie, and to provide fastening means which will effectually prevent the creeping of the track rails.

The foregoing and such other objects as

may appear from the ensuing description, 55 are attained by the means hereinafter more fully described, and by the combination, construction, arrangement and location of the parts such as illustrated in the accompanying drawings and particularly set forth in 60 the claims appended hereto.

Reference now being had to the accompanying drawings which form a part of this specification and in which similar numerals of reference indicate like parts throughout the several views, it will be seen that:—Figure 1, is a side view of the improved railway tie and rail fastening means embodying our invention, showing the track rails in cross-section secured thereto. Fig. 2, is an 70 end elevation of the same. Fig. 3, is a perspective view showing one of the clamping plates for securing the wooden blocks. Fig. 4, is a perspective view showing one of the metallic angle bars employed to prevent the 75 spreading of the wooden blocks. Fig. 5, is a top plan view of the metallic seat plate. Fig. 6, is an enlarged sectional view taken on the line 7—7, Fig. 5.

In carrying out our invention we provide 80 a railway tie of suitable or desirable dimensions throughout its length and breadth and the metallic portion of said tie with which our invention is embodied in the form illustrated in the drawings, comprises a flat 85 metal laterally extended base portion 1, and a central vertical portion 2, extending throughout the entire length of the tie, said metal portions being made of steel or other desirable metal, and formed by the metal 90 rolling mill method.

It will be observed that the track rails 3 are not supported directly on the metal portion of the tie, but are preferably seated on a metal plate 4, which rests upon the 95 upper surface of the wooden blocks 5, there being two blocks on each side of the central vertical portion of the tie, and two blocks near each end of the tie, each block having smooth straight vertical faces and 100 resting upon the upper surface of the laterally extended base portion of the tie, and projecting a suitable distance above the upright metal portion of the tie in order to thoroughly insulate the track rails from the 105 tie and to form a wide bearing surface at the upper portion thereof for the base of the track rail. The size of the blocks is

sufficient to afford the necessary strength to support the track rails and retain the rail fastening means such as plain or screw-threaded spikes, ordinarily used for securing the track rails to a wooden tie, which spikes are driven through the openings 8 in the metal tie plate 4 and into the wooden blocks.

The wooden blocks 5, are first preferably 10 impregnated with crude oil or creosote to increase their durability and are constructed rectangular in cross-section and adapted to fit accurately upon the base portion and against the central vertical portion of the tie, the dimensions of the blocks being uniform so that they may be turned upside down or either side may be used as the top or track rail supporting surface. The blocks are firmly and securely clamped in 20 place by the clamping plates which embrace them and by bolts which pass entirely through the said plates, metallic tie and wooden blocks.

The fastening means preferably employed 25 for rigidly securing each block to the body portion of the tie, consists of two headed bolts 9, screw-threaded at one end thereof, two clamping plates 10, and two securing nuts 11, each bolt passing through the opening 12, in each of the clamping plates, through the opening in the block and central upright portion of the metallic tie, whereby the blocks, tie and clamping plates are all securely locked together by the said 35 bolts 9, and the securing nuts 11 fitted to the threaded end of the bolts.

It will be seen that each of the clamping plates 10 is provided with a plurality of integral projecting spurs 12', adapted to enter the wooden blocks thereby preventing any vibratory movement of the blocks or the clamping plates when the parts are securely locked together, and the clamping plates embrace the outer wall of each block substantially the entire height of the block in 45 order to prevent the splitting of the block.

In order to insure safety by preventing the wooden blocks from spreading apart in the event the securing bolts shall become 50 broken or otherwise impaired, we provide at the outer end of each block a strong metallic right angle brace bar 13, two of said brace bars being located near each end of the tie and firmly secured to the central upright portion of the tie by a single rivet 13', one arm of each bar 13 resting against the upright portion 2 on each side thereof, and the other arm resting in contact with the outer end wall or surface of the wooden 60 block.

The metal seat plate 4 is provided with a plurality of integral upward projections 14, two at each side thereof, and one near each end, each of said projections being 65 semi-circular in form, as clearly shown in

Fig. 5, the upper surface being inclined in an upward and outward direction as shown in Fig. 7, and the plate is provided with a series of openings 8 through which the rail fastening spikes are driven. It will be seen 70 that the said projections 14, formed on the tie plate 4, are so located on the plate that the inner edges of each projection are adapted to contact with the outer side edge of the base of the track rail, and serve to prevent 75 the outward spreading of the track rails.

While the rail fastening spikes ordinarily employed may be utilized we preferably employ the screw spikes 15, such as shown in Fig. 1 of the drawings, each of said screw 80 spikes having a circular head portion 16, said head portion on its lower side being inclined from the central stem portion upwardly and outwardly, and adapted when driven into the wooden block to rest in contact with the upper inclined surface of each projection 14 and to contact with and overlap the upper surface of the base of the rail, said rounded head portion 16 being provided with an upward extension 17, adapted 85 to receive a suitable tool or wrench for driving in or withdrawing the said screw spike.

By the utilization of the block securing means hereinbefore referred to, it will be seen that there can be no shifting movement 90 of the blocks without moving the entire tie and track rail supporting means, thereby insuring and always maintaining the proper gage of the track rails and alinement of the 95 track.

It will be understood that each wooden block projects above the metal portion of the tie, thus constituting an insulating medium and preventing interference with the use of electric signaling means, and the laterally extended base portion 1 of the tie upon which the wooden blocks are supported forms a widened tie, thus materially reducing the number of ties per mile of road bed as are ordinarily employed, and the wide tie under the base of the track rail is 100 more readily retained by tamping than the narrower ties.

It will be readily perceived that each block being provided with two openings 115 therethrough and the openings in the central upright portion of the metal tie, that when the clamping plates are firmly secured to the outer side wall of each block by the fastening bolts and nuts the fiber of the wooden blocks will be tightly compressed and prevented from splitting when the rail-fastening spikes are driven therein, and the blocks will be held firmly in contact with the steel base of the tie in order to prevent 120 any up and down movement from the said base with the wave motion of the rail when the rolling stock is passing over the track rails.

It will be readily seen that our improved 125

tie is so constructed as not to interfere with the track employees in tamping up the ballast from either end or side and that one man can readily remove worn-out blocks 5 and replace new ones without disturbing the track rails or road bed.

The space between the wooden blocks and at the outer side of the said blocks is filled up with track ballast which assists in preventing any lateral, longitudinal or skidding 10 action of the railway ties during the strains to which they are usually subjected.

The wooden blocks employed are inexpensive, since the ends of logs and other pieces 15 of wood are used up that would ordinarily be cast aside as waste material.

It will be obvious that slight changes in the details of the construction hereinbefore described may be resorted to without departing 20 from the spirit of our invention.

Having thus described our invention what we claim and desire to secure by Letters Patent is:—

1. A railway tie comprising a flat metallic 25 base portion, a central integral upright portion extending throughout the length of the tie, two wooden blocks resting upon the base portion at each side of the said central portion, each block having smooth straight 30 vertical faces and projecting above the central portion, a plurality of vertically arranged clamping plates extending throughout the height of each block, each clamping plate having a plurality of inwardly projecting 35 spurs adapted to enter the wooden blocks, and bolts and securing nuts for fastening the wooden blocks to the metallic portions.

2. A railway tie comprising a central upright metallic portion extending throughout the length of the tie, an integral laterally extended base portion extending the entire length of the tie on each side of said central portion, two wooden blocks resting upon the 45 base portion at each side of the central portion, each block having smooth straight vertical faces and projecting above the central portion, two clamping plates secured vertically against the outer side face of each 50 block extending throughout the height of the block, each clamping plate having a plurality of inwardly projecting spurs adapted to enter the wooden blocks, a right angle brace bar secured to each side of the central portion, a single rivet passing through the central portion and each brace bar for securing the bars to the central portion, and bolts and securing nuts for locking the parts together.

60 3. A railway tie comprising a flat metallic base portion, a central integral upright

metallic portion extending the entire length of the tie, two wooden blocks resting upon the base portion at each side of said central portion, each block having smooth straight 65 vertical faces and projecting above the central portion, two clamping plates secured against the outer side face of each block, each clamping plate having a plurality of inwardly projecting spurs adapted to enter 70 the wooden block, said plates extending throughout the entire height of the block, a right angle brace bar secured by a single rivet to each side of the central portion intermediate the height of said central portion, two bolts passing through said clamping plates, blocks and central portion, and a securing nut fitted to the threaded end of each bolt for securely locking the said 75 clamps, blocks and bolts to the metallic portions.

4. A railway tie comprising a central upright metallic portion extending throughout the length of the tie, an integral laterally extended base portion extending the entire 85 length of the tie on each side of said central portion, two wooden blocks resting upon the base portion at each side of the central portion, each block having smooth straight vertical faces and projecting above the central portion, a right angle bar secured to each side of said central portion with one arm of each bar resting in contact with the central portion and the other arm against the outer end face of each block, a single 90 rivet passing through the said central portion for securing the bars thereto, and bolts, clamping plates and securing nuts for firmly locking the said parts together.

5. A railway tie comprising a flat metallic 100 base portion, a central upright metallic portion extending throughout the length of the tie, two wooden blocks resting upon the base portion at each side of said central portion, each block having smooth straight vertical 105 faces and projecting above said central portion, a right angle bar secured to each side of said central portion at the outer end face of each block, one arm of said bar resting in contact with the end face of the block and the other arm in contact with said central portion, a single rivet passing through the central portion and each bar for securing said bars to the central portion, two clamping plates secured against the outer side face of each block extending the entire height of the block, each clamping plate having a plurality of inwardly projecting spurs adapted to enter the wooden block, and bolts and securing nuts for firmly locking the parts together.

JACOB A. HYLE.

JACOB W. HERMAN.
